UNITED STATES PATENT OFFICE.

WILLIAM F. HELMOND, OF HARTFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed October 17, 1925. Serial No. 62,998.

This invention relates to typewriting machines, and more specifically to anti-friction carriage-bearings that promote a free easy-running, to-and-fro movement for the carriage, and the present invention may be regarded as an improvement upon the construction shown and described in the patent to Barnard, No. 949,723, dated February 15, 1910.

10 In the standard Underwood typewriting machine, the rectangular carriage-frame is supported at the front and rear by rails.

The weight of the carriage is mainly supported by sliding carriage-bearings that ride upon the rear carriage-rail, and the tendency is to increase this carrying weight by the practice of adding extra parts and attachments.

15 The release and sudden arrest of the power-driven carriage at a column-stop position, and the violent shifting of the carriage rightward against a marginal stop at the commencement of a new line, both contribute to set up violent reactions within these carriage-bearings.

20 In the development of the present invention, it is assumed that the carriage-bearings have two primary forces to resist; one, a vertical downward force due to the weight of the carriage, and the other a horizontal force due to the sudden stoppage of the carriage in both directions of its travel. The application of the "parallelogram of forces" to these two component forces, develops a resultant force 25 that bisects the axis of the rail at an angle of approximately forty-five degrees from the horizontal and at the rear. Thus in the present structure it is proposed to provide the rear of the carriage with two spaced-off carriers, each carrier provided with a horizontally-disposed anti-friction roll to bear against the front face of the cylindrical rail with the rolling flat face thereof tangent to the face of the rail at a horizontal axial position; and also provided with a second anti-friction roll to bear tangentially against the face of the rail at a point indicated by the intersection of the resultant of the forces, or in a plane approximately forty-five degrees above the horizontal axis of the rail, which provides a bearing-face against the rail that is at right angles to the direction of the resultant of the forces. The two horizontal rolls bearing against the front face of the rail, arrest the vibrations

from the heavy manifolding impact of the types, effectively co-operate with the rail to maintain parallelism between the carriage movement and the printing position, effectively avoid, through the co-operation of the 30 companion rolls, any transverse play in the carriage, and reduce the surface contact between the co-acting face-bearings to a minimum.

35 The weight of the carriage alone will maintain the two sets of anti-friction rolls in proper engagement with the carriage-rail during the usual manipulation of the typewriter, but to prevent any possible displacement of the bearings during a carriage-shifting movement, each roll-carrier is formed with the usual tongue or collar that encompasses the lower half of the cylindrical carriage-rail.

40 The added weight of the long carriage tends to develop carriage-bearings and reduces the speed of typing proportionately, but, with co-operative anti-friction roller bearings for the carriage that coat in pairs and have only two knife-edge rolling contacts with the face of the carriage-rail, a 45 large degree of bearing-friction is eliminated from the carriage-movement, which tends to offset the weight of the carriage.

45 Another important feature is the accessibility to the anti-friction rolls; each roll-carrier being secured to the carriage-frame adjacent the ends thereof, where the anti-friction ball-bearings of the rolls may be easily adjusted from time to time, which is 50 the only adjustment required for this improved anti-friction carriage-bearing.

55 Still another feature provides that instead of assembling the various parts to the carriage-frame, one by one, the rolls may first be assembled to the carrier as a complete bearing-unit and subsequently secured to the carriage as a bearing-unit and without adjustment.

Other features and advantages will here- 100 inafter appear.

In the accompanying drawings,

Figure 1 is a fragmentary transverse sectional view of a typewriting-machine carriage and supporting rails embodying the invention.

Figure 2 is a top plan view of portions of the carriage, showing the relative positions of the carriage-bearing units.

Figure 3 is a detail perspective view of one 110

of the improved carriage-bearings assembled as a unit, and adjusted to the cylindrical carriage-rail.

A type-bar 10 strikes rearwardly against 5 a platen 11, which is rotatably mounted in the ends 12 of a platen-frame. The platen-frame is supported upon a carriage 13, which is longitudinally slideable on a cylindrical rail or way-rod 14, supported at the rear of the 10 machine, as at 15, and by the usual center roll 15^a bearing upon a front rail 15^b. A "fan-fold" attachment 16 is here shown mounted upon the carriage 13 and extends rearwardly 15 in the well-known manner of the Smith-Wernery machine.

In order that the carriage 13 may be accurately positioned, I provide a pair of improved anti-friction roll-carriers or brackets designated as a unit by the reference character 20 17, and each carrier comprising a substantially horizontal body-portion 18, having a collar formed by a depending tongue 19 that curves downwardly and rearwardly to encompass the lower half of the cylindrical 25 rail 14, and locate the carriage upon said rail. The body-portion 18 is formed with a horizontal, forwardly-extending offset-ear 21, upon the face of which is mounted a horizontally-disposed anti-friction bearing-roll 22, 30 rotatable about a screw 23, threaded into the ear 21. This roll 22 may be provided with anti-friction balls interposed between the roll and screw, as shown and described more specifically in the above-mentioned patent to 35 Barnard. The body-portion 18 is also formed with a second ear 24 offset at an angle of approximately 45 degrees. This angle, of course, may be variable according to the particular design of the machine. A second anti-friction bearing-roll 25 is mounted upon a 40 screw 26 threaded into the angular ear 24, and like the roll 22, may be provided with ball-bearings to reduce axial friction to a minimum. These two bearing rolls 22 and 45 25 may be assembled to each carrier 17 as a manufactured unit and subsequently assembled to the carriage as a complete bearing-unit.

On the upper face of the horizontal body-portion 18 of the roll-carrier 17, a locating tongue 18^a is formed to enter a suitable groove of the carriage-frame, and the carrier is secured in position to an under face of the carriage by means of screws 18^b passing 50 through the carriage-frame from the top to enter threaded holes in said carrier.

A pair of these bearing-units 17 is assembled to the carriage-frame; one unit adjacent each carrier-end, as shown at Figure 2, and these two units coacting with the center roll 15^a and the front rail 15^b combine to provide a triangular or three-point suspension for the traveling carriage.

At Figure 1, it will be noted that the aperture formed in and by the tongue 19 is not a

true concentric opening relative to the cylindrical rail 14, and that certain inner face-sections of the tongue are gouged out for rail-clearance and form an irregular opening. It is desirable that the tongues 19 shall not contact with the whole surface of the rail 14 at any time. Three short bearing-face-sections 20 engaging with the cylindrical face of the rail have a free "running fit" upon the rail.

It will also be noted at Figure 1 that a horizontal axial line drawn through the rail 14 bisects a peripheral point where the roll 22 bears against the front face of the rail, and thus most effectively resists any side play or horizontal displacement in the carriage rearwardly, and provides a firm resistance to combat the impact of the types in heavy mani-folding.

In Figure 1 the direction of a component force resulting from the weight of the carriage is indicated by a vertical line A; and another force resultant from the effect of violently checking the movement of the carriage in both directions that reacts horizontally from the rear to separate the rolls 22 from contact with the rail is indicated by a horizontal line B; resolving these two component carriage-forces towards the axis of the rail 14, develops an approximate resultant force in a direction indicated by the line C, which, as shown, bisects the point where the rolls 25 contact with the face of the rail. The two rolls 25 bear the bulk of the weight of the carriage; the rolls 22 co-operate therewith to hold the rolls 25 at their indicated angular positions, and the two rolls 25, through their angular positions, co-operate with the weight of the carriage to maintain the rolls 22 in contact with the front face of the rail 14.

It will be noted that this improved carriage-bearing unit provides flat peripheral roll-faces on the carriage to bear upon the cylindrical face of the guide-rod, and that the surface engagement therebetween is practically a knife-edge rolling contact, and the carriage-movement is frictionless to a corresponding degree; and further provides that factory-assembled bearing-units can be substituted in existing machines without disturbing the adjusted relation between the types and printing face of the platen; that the collar 19 of the present detachable unit operates upon a short carriage, similar to the well-known easy running bearing of the Underwood machine, but, when a long carriage or a short carriage laden with various attachments is shuttled back and forth upon the carriage-rails with a corresponding increase in frictional drag, the anti-friction rolls bearing upon the rail prevent this extra weight from correspondingly increasing the sliding resistance at the collar-bearing faces and this collar-face-resistance becomes uniform for all weights and lengths of carriages; that the

axes of the anti-friction rolls are tangent to the bearing-face of the rail; and that the rail-engaging faces of all the rolls are parallel to their axes which effectively cut the lines of 5 resisting strain at right angles and reduce the associated friction to a minimum.

Variations may be resorted to within the scope of the invention, and portions of the improvements may be used without others.

10 Having thus described my invention, I claim:

1. In a typewriting machine, the combination with a way-rod and a carriage to be guided thereby, of guiding units articulated 15 to the carriage near the ends thereof, each unit formed to fit a locating seat upon the carriage, and means to secure the unit upon the carriage, each unit having a collar and a pair of rolls, all of said rolls being between 20 said collars, each collar fitted to said way-rod to support and guide the carriage thereon and prevent upward displacement of the carriage, each of said units having one carriage-supporting roll to relieve the friction between 25 the collar and the way-rod when the carriage is weighted, said carriage-supporting roll bearing upon the rear upper crown-portion of the way-rod to relieve the friction of the collar upon said crown, and to 30 form the main support for the weight of the carriage at that end, and the other roll in each pair mounted to bear against the front side of the way-rod to support the carriage against the blows of the type falling upon the front of the platen.

2. In a typewriting machine, the combination with a way-rod and a carriage to be guided thereby, of guiding units articulated to the carriage adjacent each end thereof, each 40 unit formed to fit a locating seat upon the carriage with means to secure each unit to the carriage, each unit including a collar operative to slide along the way-rod to effectively guide a short length of carriage, 45 said units also arranged to include a pair of relatively disposed anti-friction rolls

mounted thereon to bear upon the way-rod for a carriage-supporting rolling contact to relieve the collar of excess sliding frictional contact upon the way-rod under the heavier 50 load of a long carriage.

3. In a typewriting machine, the combination with a way-rod and a carriage to be guided thereby, of guiding units articulated to the carriage adjacent each end thereof, 55 each unit formed to fit a locating seat upon the carriage with means to secure each unit to the carriage, each unit including a collar slideable along the way-rod to guide the carriage under a normal load and a pair of rolls 60 bearing upon the way-rod for a carriage-supporting rolling contact when the carriage is heavily loaded, each pair of rolls being relatively disposed to relieve the collars of excessive frictional drag upon the way-rod 65 by presenting way-rod-bearing faces that are tangent to the rod and parallel to the axes of the rolls, to prevent wedging of the rolls and speed up the travel of the carriage.

4. In a front-strike typewriting machine, 70 the combination with a traveling carriage and a stationary rail, of a two-part carriage-bearing unit secured to the carriage to engage with the rail and guide the carriage, one part of said unit operative under a normal 75 weight of carriage, to slide over the rail with a minimum of friction, and the other part of said unit being operative under a laden carriage, to roll upon the surface of the rail without increasing the frictional engagement of the slide upon the rail.

5. In a typewriting machine, the combination with a traveling carriage and a stationary round rail therefor, of a bearing unit secured to the carriage to engage with the 85 rail, said unit including a plurality of rolls disposed around the rail to prevent displacement of the carriage, each roll having flat rail-engaging faces that are parallel to their axes and operate to prevent roll-wedging 90 strains during the travel of the carriage.
